AUTOMATICALLY CLAMPING WORK
SUPPORTING STANDMearl V. Tracy, Pasadena, Calif., assignor of fifty
per cent to Marian M. Tracy, Pasadena, Calif.

Application March 11, 1950, Serial No. 149,153

3 Claims. (Cl. 144—296)

1

This invention is directed to, and it is an object to provide, a novel work holding clamp adapted to rest on the floor and to clampingly engage and support panel-like material in a vertically edgewise position for ready and convenient working thereon.

While especially designed for use to clampingly engage and support doors, screens, sash, or the like, the device may be used effectively with many other materials which require other than manual support for the most convenient positioning for work thereon.

Another object of the invention is to provide a work-holding clamp which, when engaged with a door or the like, holds the same vertically edgewise in a laterally stable, longitudinally non-slidable position for work thereon, as for example for planing, sawing to dimension, etc.

A further object of the invention is to provide a work-holding clamp which acts, under the influence of the weight of the work, to clamp the latter in the desired position.

An additional object of the invention is to provide a work-holding clamp which is relatively light-weight, non-bulky, and manually portable, whereby to permit of its use adjacent the point of installation of the work.

It is also an object of the invention to provide a work holding clamp which is designed for ease and economy of manufacture.

Still another object of the invention is to provide a practical and reliable work-holding clamp, and one which will be exceedingly effective for the purpose for which it is designed.

These objects are accomplished by means of such structure and relative arrangement of parts as will fully appear by a perusal of the following specification and claims.

In the drawings:

Fig. 1 is an elevation of the work holding clamp in its starting position; a door being shown as initially and partly inserted into the clamp.

Fig. 2 is an elevation of the clamp in full supporting engagement with a door.

Fig. 3 is a fragmentary transverse section on line 3—3 of Fig. 2.

Fig. 4 is a fragmentary sectional plan view showing particularly one of the adjustment screw units; the view being taken on line 4—4 of Fig. 2.

Referring now more particularly to the characters of reference on the drawings, the device includes a base which comprises a pair of horizontal, elongated guide bars 1 disposed in adjacent but transversely spaced parallel relationship; said guide bars 1 being tubular, and hav-

ing tie bolts 2 which extend therethrough; said tie bolts 2 securing the guide bars 1 to an L-shaped foot 3 at each end of the device.

5 A pair of spaced upstanding slide frames 4, of generally inverted V-shape, are mounted on the guide bars 1 for sliding motion thereon in relative approaching or separating relation; the slide frames 4 being double-faced and having laterally outwardly projecting end flanges 5 through 10 which the guide bars 1 project in relatively slidable relation.

The outer end flanges 5 of each slide frame 4 have a cross bar 6 fixed therebetween, and an adjustment screw 7 is threaded through such 15 cross bar and extends outwardly toward the upstanding portion of the adjacent foot 3, bearing against the same. By adjusting each screw 7 the outward limit of motion of each slide frame 4 may be regulated.

20 A pair of upstanding posts 8 are disposed between the slide frames 4 in spaced, parallel relation; said posts 8 terminating, at their lower ends, some distance above the guide bars 1. Each post 8 is connected to the corresponding slide frame 25 4 by vertically spaced, pivotally attached parallel links 9, whereby said posts are swingable between a raised, laterally outwardly retracted position, and a lowered, laterally inwardly advanced position, as shown in Figs. 1 and 2, respectively. This result is accomplished for the reason that each set of parallel links 9 extends at an upward and inward incline from the point of pivotal connection with the related slide frame 4.

35 35 A tension spring 10 is connected between each pair of parallel links 9, in a manner tending to swing the same upwardly whereby to move the posts 8 to their raised, laterally outwardly retracted position. Each post is fitted, on its inner face, with a pair of vertically spaced and adjustable cushion pads 11, each comprising a laterally inwardly opening rubber cup, as shown, held in place by an attachment disc 12 in the bottom of the cup, and a bolt 13 which passes through a vertical slot 14 in the related post 8. The cushion pads 11 are adjusted, on the posts 8, so that they oppose each other in sets.

40 A pair of transverse, lapping rods 15 extend between the posts 8 at the lower ends of the latter, one rod being affixed to one post and the other rod being affixed to the other post, and such rods being of a length that they remain in lapping relation irrespective of the spacing between the posts 8.

45 Such lapping rods 15 pass, at a point between

the posts 8, through a ring 16 fixed to the bottom of a rockable platform 17 which extends lengthwise through the device intermediate the upstanding slide frames 4.

When the above described device is in use it rests upon the floor, and the slide frames 4 are separated to the maximum limit which the adjustment screws 7 permit; the springs 10 initially holding the posts 8 in raised, laterally outwardly retracted position, as in Fig. 1. Thereafter, the work, here shown as a door 18, is lowered, vertically edgewise, between the opposed sets of cushion pads 11, as shown in Fig. 1, and thence the work is engaged, at its lower edge, on the rockable platform 17 and released or pushed downwardly. When this occurs the weight of the work, as supplemented by the downward push, causes the rockable platform 17 to move downward, carrying the posts 8 therewith; the posts as they move downward shifting—under the influence of the parallel links 9—to a lowered, laterally inwardly advanced position, positively clamping the cushion pads 11 against opposite sides of said work.

Thereafter, the work is effectively clamped and supported in a vertically edgewise position for working thereon; the positive frictional engagement of the cushion pads 11 with opposite sides of the work not only preventing any lateral teetering of said work, but preventing longitudinal sliding thereof on the platform 17, the latter being rockable in order to matchingly engage the lower edge of the work.

In order to compensate for work of different thickness and to assure that the cushion pads 11 positively engage the work on opposite sides when the platform lowers, the adjustment screws 7 are regulated to alter the initial spacing of the slide frames 4.

Under certain conditions it may be desirable to lock the device in a work clamping position, and to this end one of the slide frames 4 is formed with a row of holes 19 which extend upwardly along the inner edge of said frame. After the posts 8, together with the parallel links 9, are lowered to work clamping position, a cross pin (not shown) is inserted through the hole 19 next above the adjacent lower link 9, preventing said link from swinging upwardly and thus maintaining the device in a work clamping position.

The bars 1 instead of being tubular, may be of solid stock; in which case feet 3 are secured to the bars by cap screws rather than continuous tie bolts.

The device may also be used as a dolly, if desired, by merely mounting the feet 3 on casters.

The described work holding clamp provides a very practical and readily manually portable device for the intended purpose, and when in use maintains the work in a most convenient and accessible position.

From the foregoing description it will be readily seen that there has been produced such a device as substantially fulfills the objects of the invention as set forth herein.

While this specification sets forth in detail the present and preferred construction of the device,

still in practice such deviations from such detail may be resorted to as do not form a departure from the spirit of the invention, as defined by the appended claims.

Having thus described the invention, the following is claimed as new and useful, and upon which Letters Patent are desired:

1. A work supporting clamp comprising a base, a pair of spaced upstanding frames on the base, a pair of spaced upright posts between the frames, means connecting the posts and corresponding frames for movement of the posts between a raised laterally retracted position and a lowered laterally advanced position, means mounting the frames on the base for horizontal adjustment of the frames relative to each other whereby to alter the initial spacing of the posts from each other, work engaging elements on the opposing faces of the posts, an elongated work engaging platform extending between the posts at their lower ends and in a direction parallel to the opposing faces of said posts, and means supporting the platform from the posts for lengthwise rocking movement in a vertical plane parallel to the opposing faces of the posts and allowing of independent lateral movement thereof relative to the posts.

2. A work supporting clamp comprising a base, a pair of spaced upstanding frames on the base, a pair of spaced upright posts between the frames, means connecting the posts and corresponding frames for movement of the posts between a raised laterally retracted position and a lowered laterally advanced position, means mounting the frames on the base for horizontal adjustment of the frames relative to each other whereby to alter the initial spacing of the posts from each other, work engaging elements on the adjacent faces of the posts, adjacent and horizontally parallel members both spanning the gap between the posts adjacent and below their lower ends, one member being secured on one post and the other member being secured on the other post, a work supporting platform above the members, and a sleeve fixed on the underside of the platform and slidably receiving both members therethrough.

3. A device as in claim 2 in which the horizontally parallel members are circular in cross section to permit the sleeve to rock about them; the platform being elongated in a direction at right angles to the axis of rocking.

MEARL V. TRACY.
